FLOYD N. PERKINS, OF FREEPORT, ILLINOIS, ASSIGNOR TO ARCADE MANUFACTURING COMPANY, OF FREEPORT, ILLINOIS, A CORPORATION OF ILLINOIS.

SPRING-LATCH.

1,109,358.

Specification of Letters Patent.

Patented Sept. 1, 1914.

Application filed April 15, 1914. Serial No. 831,981.

To all whom it may concern:

Be it known that I, FLOYD N. PERKINS, residing at Freeport, in the county of Stephenson and State of Illinois, have invented 5 certain new and useful Improvements in Spring-Latches, of which the following is a specification.

My invention relates to certain improvements designed to afford a spring latch 10 adapted for use upon doors which it is desirable to open by a pull upon the side toward which the door opens or by a push upon the opposite side.

The purpose of the invention is to provide 15 a simple, compact and efficient device of this sort which can be manufactured cheaply and also easily applied to the particular use which may be found desirable.

To this end the invention consists in certain 20 novel features of construction, form and arrangement the preferred embodiment of which will be fully illustrated and described herein and the essential characteristics of which will be clearly defined in the 25 claims appended hereto.

In the drawings Figure 1 is a front elevation 30 of a complete latch; Fig. 2 is a transverse section in the line 2—2 of Fig. 1 looking in the direction of the arrow 2 and showing the parts in the locked or closed position and Fig. 3 is a similar section showing the parts in the unlocked position at the point where the closing of the door has brought them in contact and a further closing movement 35 will trip the latch and bring it into the position seen in Fig. 2.

Referring to these drawings A is a suitable casing provided with screw holes, a , a , by means of which it is designed to be 40 secured to the casing or frame against which the door closes and with outwardly projecting ears, a^1 , a^1 , between which is hung a rocking lever, B, by means of a pivot pin, b. This lever has projections radiating from 45 the pivot pin in the form of a foot, b^1 , two fingers, b^2 , b^3 , and an arm, b^4 . To the bottom of the casing is secured a cup, C, in which is confined under longitudinal compression a coiled spring, D, pressing upwardly 50 against a spring table, E, having a depending leg or spring arbor, e, which holds it in place upon the spring. The foot, b^1 , rests upon the spring table, moving thereon from the position seen in Fig. 2 to 55 that seen in Fig. 3, the limits of this move-

ment being fixed by the fingers b^2 , b^3 , the former engaging the casing as seen in Fig. 3 to check the movement in one direction and the latter engaging the spring table as seen in Fig. 2 to check the movement in the other 60 direction.

It should be noticed that in Fig. 2 the line of the thrust of the spring upon the foot b^1 is well to the left of the pivot of the arm so that the force of the spring is 65 strongly applied to hold the arm in the position shown. On the other hand in Fig. 3 the thrust of the spring upon the foot is substantially in line with the pivot so that the arm will naturally remain in the position shown and be held there by the friction of the parts until force is applied to shift the line of said thrust toward the position shown in Fig. 2.

On the under side of the casing A and 70 within the chambered portion thereof is an incline, a^2 , see Fig. 2, which aids the rocking lever B to swing the spring table slightly in passing from the position seen in Fig. 3 to that seen in Fig. 2. This increases 75 the effectiveness of the spring by giving it a better purchase upon the rocking lever than would be otherwise obtained.

A handle, F, is provided with screw holes, f , f , by means of which it is intended to be 80 fastened to the door and has a laterally projecting arm, f^1 , which during the latter portion of the closing of the door strikes the finger b^3 as seen in Fig. 3 and rocks the lever B toward the position seen in Fig. 2 until 85 the spring takes hold and completes such movement.

In the end of the lever B is a perforation, b^5 , and in line therewith in the position seen in Fig. 2 is a perforation, f^2 , in the handle F 90 affording a convenient means of applying a padlock or in certain possible cases a pin to hold the latch against the movement ordinarily effected by forcibly moving the door.

Starting with the parts in the positions 95 seen in Fig. 2 the opening of the door forces the handle portions, including the arm f upward, crowding the arm b^4 of the lever B ahead of it until the latter swings backward out of the way of the arm f^1 and is held there by the force of the spring D. When 100 the door is closed the arm f^1 of the handle F strikes the finger b^3 and rocks the lever back into the position seen in Fig. 2 in which the tension of the spring D is applied to the 105 110

door handle to hold the door in the closed position.

I recognize the possibility of variation in the particular construction, form and arrangement of the parts herein described and hence do not limit myself to the exact details shown but will point out the essential features thereof in the following claims in which it is my intention to cover all of the patentable novelty contained in my invention over the prior art.

I claim as new and desire to secure by Letters Patent:—

1. In a device of the class described the combination with a part for attachment to the door having a suitable projection, of a casing adapted for attachment to the frame, a rocking lever pivoted to said casing having an arm for engagement with said part upon the door, suitable fingers to limit its movement in either direction and a radially projecting foot, a cup secured to said casing, a spring under longitudinal compression in said cup, a spring table resting upon the spring and pressing upon said foot to hold the arm alternately in the locked or unlocked position and engaging one of said fingers in one position of the lever.

spring table in its upward movement and rocking said table and spring in the direction in which the foot of the rocking lever is moving when passing toward the locked position.

2. In a device of the class described the combination with a part for attachment to the door having a suitable projection, of a casing adapted for attachment to the frame, a rocking lever pivoted to said casing having an arm for engagement with said part upon the door, suitable fingers to limit its movement in either direction and a radially projecting foot, a cup secured to said casing, a spring under longitudinal compression in said cup, a spring table resting upon the spring and pressing upon said foot to hold the arm alternately in the locked or unlocked position and engaging one of said fingers in one position of the lever.

In witness whereof I have signed the above application for Letters Patent at Freeport, Illinois, this 25th day of March, A. D. 1914.

FLOYD N. PERKINS.
